UNITED STATES PATENT OFFICE

2,557,870

WATCHMAN'S CLOCK

Gerard Gustav Gruettner, Atlanta, Ga., assignor
to Lathem Time Recorder Company, Atlanta,
Ga.

Application March 29, 1949, Serial No. 84,043

3 Claims. (Cl. 346—144)

1

This invention relates to a watchman's clock of the type carried by watchmen and used in connection with a plurality of keys which are secured, ordinarily by chains, at as many stations located at different points in the premises to be guarded.

A primary object of the invention is to provide a clock which will make an easily legible and accurate record on paper dials of conventional character used in the clock showing the times at which the different keys were inserted and turned in the clock, there being provided an improved mechanism for suitably embossing the said paper dial.

Another object of this invention is to provide an assembly, hereinafter referred to as the assembly for punching and embossing a paper dial, mounted upon the hinge used to secure the casing and the door, this incorporation of the said assembly with the hinge structure resulting in a simplification in the manufacture of the devices, and the interchangeability of the said assemblies on differently sized and otherwise differently formed clocks.

Another important object, closely allied with the preceding object, is to provide the paper dial punching and embossing assembly on the hinge so that the parts carried by the door and the parts carried by the casing are preserved in strict registration due to the proximity to the hinge pin. Otherwise stated, incorporation of the said assembly with the hinge allows part of the assembly to be mounted on the door while another part can be mounted on the casing, without loss of accurate registration of the two parts.

Still another object of this invention is to provide means, incorporated with the hinge structure, for recording on the paper dial the time when the door is closed, thus making it difficult for any unauthorized person to open and close the door without leaving a permanent record of the exact time when this was done.

And a last object to be mentioned specifically is to provide a watchman's clock of the character mentioned above which will give efficient and durable service, which will be simple and accurate in operation, and easily repaired and adjusted when necessary, which has several devices incorporated therewith to prevent unauthorized tampering with the mechanism, and which will be relatively simple and inexpensive to manufacture.

With these objects definitely in view, this invention resides in certain novel features of construction, combination and arrangement of ele-

ments and portions as will be hereinafter described in detail in the specification, particularly pointed out in the appended claims, and illustrated in the accompanying drawings which form a material part of this application, and in which:

Figure 1 is an elevational view of the assembled clock, showing the door opened and disposed vertically while the casing is disposed horizontally;

Figure 2 is a horizontal sectional view, taken on the line 2—2 in Figure 1;

Figure 3 is a vertical sectional view taken on the line 3—3 in Figure 1;

Figure 4 is a vertical sectional view designed particularly to indicate the position of the arm carrying a pointed member to prick the paper dial when the door is nearly closed;

Figure 5 is a view similar to Figure 4 but showing the arm retracted into the position assumed when the door is fully closed;

Figure 6 is a vertical cross sectional view, taken substantially on the line 6—6 in Figure 5 and showing the key inserted in the slot provided therefor and before the key is turned;

Figure 7 is a view similar to Figure 6 and showing the position of the various elements when the key has been inserted and turned after such insertion;

Figure 8 is a fragmentary top plan view of the assembled device with the part of the assembly carried by the door shown in the position assumed when the door is closed, the door being removed in this figure;

Figure 9 is a fragmentary top plan view of that part of said assembly which is mounted upon the casing; and

Figure 10 is a three dimensional view of the key used with this clock.

Similar characters of reference designate similar or identical elements and portions throughout the specification and throughout the different views in the drawings.

Referring now to the drawings in detail, this invention includes a casing 10 having an apertured front panel 12 through which the dial of the clock mechanism may be viewed. The casing 10 will contain a clock mechanism, thought unnecessary to be illustrated in this application, having a spindle 14 projecting through a panel 16 on the side of the said mechanism remote from the front apertured panel 12, and this panel 16 is rigidly secured to the casing 10 and seals the clock mechanism therein. The spindle 14 will carry means 18 of conventional form for

securing a paper dial 20 upon the end of the spindle.

A cover 22, preferably formed with a rim flange 24 to fit within a corresponding rim portion of the casing 10, is hinged to the casing by the assembly generally indicated at 26 in Figures 1, 2 and 8. The cover 22 will be secured in closed position on the casing 10 by a latch 28 which engages a channel member 30 on the panel 16, these members being best shown in Figures 1 and 2. The hinge may be thought of as including an attachment plate 32 secured to the panel 16 on the casing and an attachment plate 34 secured, ordinarily by screws, to the inside surface of the cover 22, and it should be particularly noted that the plate 34 is offset by an integral block member 36. The numeral 38 identifies the screws used to secure the plate 34 to the cover 22. The hinge pin 40 should be, at least in part, set into the casing and/or the cover 22 so as to make it difficult to remove this hinge pin when the cover is closed and locked.

An arm 42 of U-shape is pivoted as indicated at 43 to the block member 36 and this arm carries a pointed member 44 on the bight portion thereof, the pointed member 44 being dimensioned and positioned to register with and terminally enter the bore 45 in the plate 32 when the door is in nearly closed position. This action is best illustrated in Figure 4. A pair of spiral springs 46 will be secured under tension between lugs provided on the plate 34 and lateral portions of the arm 42 adjacent to the pivot pin 43 but disposed on the side thereof remote from the casing, so that the arm will be biased into a position causing the pointed member 44 to pierce the paper dial 20 when the cover 22 is nearly closed. Heel portions 47 on the U-shaped arm 42 are positioned and dimensioned to engage adjacent portions of the plate 32 when the cover 22 is in fully closed position, thus raising the pointed member 44 out of engagement with the paper dial 20 and allowing this paper dial to turn with the spindle 14.

The block member 36 has a key hole 48 formed therein and the plate 34 has an elongated member 50 integral therewith and defining a channel registering with the key hole 48. This channel 50 accepts that part of the key 52 indicated at 54, the drawings indicating the channel 50 and the member 54 as being cylindrical. If reference be had to Figure 10, it will be noted that a representative key will also include a plate 56 with an upraised portion 58 having an embossed numeral 60 thereon, located according to the station desired to be identified by the particular key. The key will also have a slot 62 giving clearance to the block member 36 when the key is turned, and an aperture 64 will be provided in the plate 56 to receive a pin 66 selectively insertable in the threaded apertures 68, best indicated in Figures 8 and 9, thus making it possible to limit the use of the key according to the positioning of the pin 66 in these apertures 68. As a further precaution against unauthorized use of keys in the clock, an angle iron guard 70 is screwed onto the plate 32 adjacent to the key hole 48 when the cover is in closed position and a notch 72 in this member 70 is dimensioned and positioned to accept the upraised portion 58 of the key 52 when the proper key is used, while refusing entrance to keys of other configuration.

A roller 74, having reduced terminal portions 76 disposed in slots 78 in a cross member 78 preferably integral with the attachment plate 34 and

in the corresponding portion of the block member 36, is engaged by the edge of the plate 56 of the key when the key is turned after insertion. A leaf spring 80 is secured to a flange 82 formed integral with the plate 34 and the ends of the leaf spring 80 engage the reduced end portions 76 of the roller 74 to bias the same toward the key, and as a result a snap action is achieved whereby the key is snapped forcefully toward the plate member 84 having embossing characters 86 thereon and rigidly secured to the face of the plate 32. Ordinarily there will be a plurality of characters 86 on this plate 84 and these characters will be linearly arranged to correspond with markings on the paper dial 20 and with the characters 60 on the different keys 52.

The operation of this invention will be clearly understood from a consideration of the drawings and the above description of the mechanical details thereof, taken in connection with the above recitation of the objects of this invention. Further description would, therefore, appear to be unnecessary.

Minor modification from the embodiment disclosed in the drawings and in the above specification may be resorted to without departure from the spirit of this invention which is defined as to scope in the sub-joined claims.

Having described the invention, what is claimed as new is:

1. A watchman's clock including a casing and a cover, a hinge connecting the cover on the casing, a clockwork mechanism in the casing and having a spindle to support and to rotate a paper dial, a panel adjacent the cover and covering said mechanism within the casing, a paper dial punching and embossing assembly on said hinge, said punching assembly comprising an arm pivoted on said hinge and extending diametrically across the inside of the cover, a pointed member depending from the end portion of said arm remote from the hinge, means to bias said arm to pivot toward said panel when the cover is opened, said arm having a heel portion engaging a portion of the hinge and forcing said arm to retract toward said cover when the cover is closed.

2. A watchman's clock including a casing and a cover, a hinge connecting the cover on the casing, a clockwork mechanism in the casing and having a spindle to support and to rotate a paper dial, a panel adjacent the cover and covering said mechanism within the casing, a paper dial punching and embossing assembly on said hinge, said hinge having a pair of attachment plates, a member having embossing characters thereon mounted on one of said plates, a key having an embossing character thereon, the second of said plates having a slotted portion to receive said key, means to guide said key into position with its embossing character registering with one of the characters on said member, and a spring biased roller to attribute a snap action to the key when the same is turned in said slotted portion.

3. A watchman's clock including a casing and a cover, a hinge connecting the cover on the casing, a clockwork mechanism in the casing and having a spindle to support and to rotate a paper dial, a panel adjacent the cover and covering said mechanism within the casing, a paper dial punching and embossing assembly on said hinge, said hinge having a pair of attachment plates, a member having embossing characters thereon mounted on one of said plates, a key having an embossing character thereon, the second

of said plates having a slotted portion to receive said key, means to guide said key into position with its embossing character registering with one of the characters on said member, a spring biased roller to attribute a snap action to the key when the same is turned in said slotted portion, an arm carrying a pointed member and pivoted on one of said plates, spring means to bias the arm to pivot toward the other of said plates, and means to pivot the arm away from the last mentioned plate when the cover is fully closed on the casing.

GERARD GUSTAV GRUETTNER.
